SPINNING-MULE.

1,079,302.

Specification of Letters Patent.

Patented Nov. 18, 1913.

Application filed October 12, 1909. Serial No. 522,235.

To all whom it may concern:

Be it known that I, JOHN LOWE, a subject of the King of Great Britain, and a resident of New Bedford, in the county of Bristol 5 and State of Massachusetts, have invented an Improvement in Spinning-Mules, of which the following description, in connection with the accompanying drawings, is a specification, like letters on the drawings 10 representing like parts.

This invention relates to spinning mules, and in the embodiment herein selected for purposes of illustration, in order that the principle of the invention may readily be 15 understood, it is an improvement upon the United States Patent to Henry S. Golland, No. 873,422, December 10, 1907.

In the drawings;—Figure 1 is a view, partially in side elevation and partially in section, of a portion of a spinning mule having my invention applied thereto; Fig. 2 is a front view with parts removed, of a portion of the mechanism shown in Fig. 1; Fig. 3 is a detail representing in side elevation a portion 20 of the mechanism for operating the parts shown in Fig. 1; Fig. 4 is a front elevation of the construction shown in Fig. 1; Fig. 5 is a vertical sectional view taken upon the broken line 5—5 of Fig. 4; Fig. 6 is a 25 view partially in side elevation and partially in vertical section of a portion of my invention; Figs. 7 and 8 are views in side and end elevation of the preferred form of means for placing the faller locking lever in operative 30 engagement with the coppering rail; Fig. 9 is a view partially in side elevation and partially in vertical section and showing the preferred mechanism for operating the faller; Fig. 10 is a diagram illustrating the 35 movements of the cross wind guide and the faller to produce the cross wind formation of the cops; and Fig. 11 is a view mainly in side elevation showing the preferred form of spindle driving mechanism.

The patent to Golland, No. 873,422, discloses a spinning mule in which the yarns are vibrated as the mule carriage runs in, by means of a guide rod or wire placed between the winding spindles and the winding faller 40 wire, thereby to lay the yarns in cross windings. To this end, the cross wind wire had imparted thereto a number of vibrations during each winding run of the carriage. The faller wire, however, was held stationary 45 during each winding run and received only

such very slight forward movement as was necessary to build the cops, such movement being synchronous with the gradual elevation of the cross wind wire. I have ascertained by practical tests that a cop wound in 50 the manner described in said patent is not of uniform hardness throughout, this defect being due to the fact that the cross wind wire does not control the tension of the yarns but permits the formation of slack, particularly when said cross wind wire moves downward or toward the faller wire which, as previously stated, is stationary at this time, and therefore cannot apply proper tension 55 to the yarns.

In order to overcome the defects to which I have referred I provide means to prevent the formation of slack during the cross winding movements of the cross wind guide and preferably accomplish this result by imparting to the faller wire a plurality of movements during a single winding run of the mule carriage corresponding in number to the cross wind movements of the cross wind guide, these movements of the guide 60 and faller wire occurring substantially simultaneously but preferably differentiated in extent for purposes hereinafter described. It is apparent, however, that the said movements of the cross wind guide and faller wire 65 need not be differentiated but may be the same both in time of occurrence and in extent.

The cross wind guide employed by me is preferably operated by the same general 70 mechanism disclosed in said patent and constitutes the cop building mechanism. The faller to which I impart the movements heretofore referred to as conforming substantially to the movements of the cross 75 wind guide, is employed by me not as a cop building mechanism but as a tensioning and yarn directing mechanism. In order to impart said movements to the faller, preferably I employ a coppering rail presenting 80 certain novel characteristics to be herein- 85 after more particularly set forth.

Referring more particularly to the drawings, the mule carriage is represented at 1, it having mounted thereon the usual spinning spindles 2 driven in suitable manner. At each side of the head stock the mule carriage 1 is provided with a rock shaft or rod 3 rotatably mounted in bearings 4 provided by "pokers" 5 which are slidably in 90 95 100 105 110

brackets 6 secured to the front of the mule carriage 1. At proper intervals along the length of the rock shafts 3 are carried bent fingers 7 through one end of which pass the 5 cross wind guide or guides 8, preferably intermediate the spindles 2 and the faller wire 9 shown in Fig. 9.

In order to rock the shaft 3 carrying the cross wind guide 8 at each side of the head 10 stock, I may provide any suitable mechanism but have herein shown in Fig. 4 a rack 10 fixed to the floor, and secure a bracket 11 to the front of the mule carriage 1 at the end near the head stock, said bracket 15 providing bearings for a shaft 12 carrying a pinion 13 shown in dotted lines in Fig. 4 and meshing with the rack 10. The pinion 13 is here shown as carrying a beveled wheel 14 meshing with a beveled wheel 15, shown 20 in Fig. 5 as formed upon a sleeve 16 rotatable in bearings in the bracket 11. Preferably the bracket is of such construction as to inclose the pinion 13 and beveled 25 wheels 14 and 15. The sleeve 16 is here shown as inclined to the vertical corresponding to the angle of inclination of the spinning spindles 2, and slideable within the 30 sleeve 16 but rotatable therewith by means of a slip feather and groove, as indicated 35 in Fig. 5, is a shaft 17, the upper end whereof is loosely socketed in a cross head 18 shown in Figs. 1, 4 and 5. The said cross head 18 is loosely connected to links 19 which are also secured to an adjustable 40 crank 20 shown in Fig. 1 as connected to the rock shaft 3 to rock the same, and thereby to impart to and fro cross wind movements to the cross wind guide 8.

To enable the shaft 3 to be rocked through 45 the medium of the crank 20, links 19 and connecting shaft 17, the said shaft 17 is reciprocated within the sleeve 16, in addition to partaking of the described rotary movement of said sleeve. This reciprocatory movement should be the shortest when 50 first commencing to wind upon the bare spindles, so that the throw of the cross wind guide 8 will also be short, in order to form a thick or blunt bottom. The throw or 55 traverse of the said cross wind guide 8 should be automatically and gradually increased during the formation of the cop bottom, the maximum traverse of the said guide being attained when the cop bottom 60 is completed. After the cop bottom has been formed the maximum traverse of the said cross wind guide is maintained throughout the entire building of the cops. In order to effect this result, I have in the selected embodiment of my invention provided the shaft 17 with a boss 21 shown most clearly in Fig. 5 and provided with two cam grooves 22 and 23. Inclosed within a casing 24, herein forming a bearing for the shaft 65 17 are two plates 25 and 26 shown also in

Fig. 2, in which figure the front of the casing 24 has been removed. The plates 25 and 26 are provided respectively with bowls 27 and 28 rotatable on studs 29 secured to the said plates 25 and 26. The cam groove 23 is of less pitch than the cam groove 22. If therefore the plate 25 carrying the bowl 27 be held fixed while the plate 26 is allowed to rise and fall freely in the casing 24, the shaft 17 when rotated in the manner described will also be reciprocated within and relative to the sleeve 16 to its minimum extent, owing to the influence of the bowl 27 upon the cam 23. If the said fixed plate 25 be gradually released so as to allow it to rise and fall within the casing 24 to an increasing extent and also at the same time the loose plate 26 be gradually locked within the casing to prevent its rising and falling, the influence of the bowl 27 upon the cam 23 will be diminished while the effect of the bowl 28 upon the cam 22 will be correspondingly increased. As the bowl 28 engages with the cam 22 having the larger throw or pitch, the result is that the shaft 17 is gradually reciprocated to an increased extent until the cop bottom is finished, when the plate 25 is entirely released. The plate 26 is at that time locked so that the bowl 28 being substantially immovable, its influence upon the cam 22 of greatest pitch causes the shaft 17 to receive its greatest reciprocatory movement within the sleeve 16, and thereby to vibrate the cross wind guide 8 through an arc of a circle to its maximum extent, as indicated in dotted lines in Fig. 1. To effect the locking and releasing of the plates 25 and 26, they are each loosely pivoted by pins 30, 31 to slide plates 32, 33, shown most clearly in Figs. 2 and 5, said plates being provided with slots 34. Within the slots 34 are positioned pins 35, carried by a boss 36 on a bar 37, here shown in Fig. 2 as slideable in a straight line within the casing 24. In the position shown in Fig. 2, the pins 35 come below the pin 31 which loosely pivots the plate 33 to the plate 26, and said plate 26 is thereby locked or held stationary. The plate 25 is free or capable of oscillating within the casing 24, but if the bar 37 be moved to the left viewing Fig. 2, to bring the pin 35 immediately below the pin 30, which pivots the plate 32 to the plate 25, the said plate 26 is thereby gradually released and the plate 25 is gradually locked. This movement of the bar 37 is preferably accomplished by a lever 38 having a slotted end 39, shown most clearly in Fig. 1, engaged with the pin 35 upon said bar 37, said lever 38 being pivoted at 40 upon a depending portion 41 of the casing 24. The opposite or lower end of said lever 38 is provided with a pin 42 engaging a vertically arranged cam way or guide 43 in a bracket 44 extending upwardly from 45

the bracket 11, as shown most clearly in Figs. 4 and 5. The lower portion of the cam way 43 is inclined as represented in Fig. 4, so that when the pin 42 of the lever 38 is engaged therewith the pin 35 is positioned beneath the pin 30, or in the position opposite that shown in Fig. 2. By mechanism to be described, the casing 24 is gradually elevated during the building of the cops and the pin 42 upon the lever 38 is thereby moved into the vertical portion of the cam way 43, thus moving the lever 38 to the right as indicated in Fig. 2, thereby to position the pin 35 beneath the pin 31 and to lock the plate 26 into position. During the running out of the mule carriage in the operation of spinning, the yarns are delivered by the rolls in the usual manner. The yarns are then directed from the extreme tips of the spinning spindles 2 as is well known, and in this position the yarns are out of reach of the cross wind guide 8 which, although vibrating, cannot touch the yarns and is thus inoperative. The counterfaller shaft is indicated at 45 in the several figures, the faller shaft being indicated at 46, and the faller at 47 and carrying the faller wire 9. When the mule carriage runs in to wind the yarns on the spindles, the faller wire 9 is depressed by mechanism to be hereinafter described to direct the yarns to the bases of the cop noses, as indicated in Fig. 9, and the cross wind guide 8 is moved to and fro longitudinally of the spindles a plurality of times during each winding run of the carriage, thereby to raise and lower the yarns between the bases and apices of the cop noses, and thus to lay yarns upon the spindles in a cross wind.

In order to build the cops a coppering motion is provided synchronously to raise the cross wind guide 8 and the faller wire 9 to the required slight degree each time the mule carriage runs in. For this purpose I have herein disclosed the following mechanism: The shaft 12 carrying the pinion 13 meshing with the rack 10 upon the floor carries also as shown in Fig. 3 a disk 48 having a pivoted pawl 49 which is inoperative on the run out of the carriage, but which when the carriage runs in and the yarns are being wound upon the spindles comes into contact with and actuates a lever 50 carrying the pawl 51 which intermittently rotates a ratchet wheel 52 fixed upon a shaft 53 carried in suitable bearings in the frame of the mule carriage. The ratchet wheel 52 is locked by a detent 54 shown in Fig. 1, and the motion of the shaft 53, shown also in dotted line in Fig. 9, is communicated by a worm 55 indicated in dotted lines in said figure, to a worm wheel 56 fixed on a vertical screw shaft 57 mounted in suitable bearings and having a worm 58 gearing with the worm wheel 59 on the shaft 60 mounted in suitable

bearings in the mule carriage. The shaft 60 thus slowly rotated is provided with a pinion 61 shown in Fig. 1, which meshes with a rack 62 secured to the casing 24 so as gradually to raise the said casing and the vertical shaft 17 therewith as the cops are being formed, the casing having suitable guiding brackets permitting said sliding movement. The shaft 60, as shown in Fig. 6, is also provided with a suitable number of pinions 63 meshing with racks 64 secured to the "pokers" 5 carrying the rock shaft 3, as already stated. In this manner, as the carriage runs in the cross wind guide 8, in addition to being oscillated through the arc of a circle as described, also is raised the slight degree necessary to build the cops by the lifting of the "pokers" 5 and the casing 24, also acting as a "poker."

The faller wire 9 is not held stationary during the running in of the carriage, as disclosed in said Golland patent, but has imparted thereto during each winding run of the carriage a plurality of cross wind tensioning movements equal in number to the cross wind movements imparted to the guide 8. Inasmuch as the cross wind guide 8 lays the yarns upon the cops, the faller wire 9 is employed to tension the yarns so as to prevent the formation of slack particularly at that point in the laying of the cross wind when the cross wind guide, having been elevated repeatedly during each winding run of the carriage, is about to descend. Inasmuch as the faller wire in the Golland patent was held stationary during these repeated rising and falling movements of the cross wind guide, when the said guide began each downward movement the yarn became slack as the guide was withdrawn from beneath them, and the faller wire being stationary could not take up the slack nor maintain the tension. The counterfaller wire, which in the Golland patent was of the usual type, did not maintain this tension.

In Fig. 10, I have illustrated diagrammatically the movements imparted to the cross wind guide and to the faller during a single winding run of the carriage. In said figure, the extreme upward position assumed by the cross wind guide 8 during a single winding run is represented at 8^a, there being, in this embodiment of my invention, four to and fro cross wind movements imparted to the said guide during each winding run of the carriage. The extreme downward position assumed by the said cross wind guide during each winding run is indicated at 8^b. Similarly the extreme upper and extreme lowermost positions of the faller wire are indicated at 9^a and 9^b respectively, it being evident that for each to and fro movement imparted to the cross wind guide 8 a corresponding to and fro movement is imparted to the faller wire 9. Within the scope of

my invention, the movements imparted to the cross wind guide and to the faller wire may be identical both in time of occurrence and in extent of movement, but preferably and as here shown they are somewhat differentiated in order to impart a slightly greater tension to the yarns as they are laid upon the noses of the cops, or in other words, when the yarn is being wound upon the portion of the cop that is of the least diameter. In order to accomplish this result, I have, in this embodiment of the invention, terminated the upward movement of the faller wire 9 prior to the termination of the corresponding upward movement of the cross wind guide 8, with the result that the continued upward movement of the cross wind guide imparts a slightly greater degree of tension to the yarn as it is laid upon the noses of the cops. Either simultaneously with or slightly after the commencement of the downward movement of the cross wind guide 8, according to which form of my invention may be employed, the faller guide 9 commences to move downward, thereby maintaining the proper tension upon the yarns and preventing the formation of slack, and thus absolutely controlling the angle of delivery of the yarns past said cross wind guide to the cops. It will be evident that were the faller wire not moved in the manner indicated, that the angle of delivery of the yarns past the cross wind guide 8 would not be maintained when the guide is moved from beneath it.

Although I have described the tensioning of the yarns as accomplished during the cross winding movements of the guide 8 by the corresponding movements of the faller wire 9, this tensioning may be accomplished in any other suitable manner.

In order to effect the described movement of the faller, I have herein provided a coppering rail 65 shown in Fig. 9, the upper edge 66 thereof being in a horizontal plane and not generally inclined from front to rear, as customarily used in the formation of cops not of the cross wound character. At front and rear the coppering rail is provided with lateral pins 67 riding upon inclined shoes 68 of equal slope, the said shoes being gradually moved longitudinally in the customary manner by screw shaft 69 engaging nut 70 upon one shoe 68 and having a ratchet 71, the pawl 72 whereof is shifted by a cam 73 upon the carriage of the mule at each winding run. The shoes 68 are connected by slide rod 74, so as to move in unison and to move the shoes 68 equally, thereby to lower the coppering rail 65 equally at opposite ends, thus gradually elevating the faller wire 9 to build the cops. The coppering rail has a level upper edge and is moved uniformly at opposite ends, because it is not used to form the cop bottom as heretofore,

but is employed merely to give tension to the yarns through the faller wire.

The faller shaft 46 is provided with the usual locking lever 75 provided at its lower end with a block 76 adapted to be positioned during each winding run upon a bowl 77 mounted upon the upper end of a bracket 78 mounted for sliding movement in suitable guides in the mule carriage. The lower end of said bracket 78 is provided with a bowl 79 adapted to ride upon the upper edge of the coppering rail 65. The locking lever 75 is provided with a monkey tail 80 adapted to be struck by a projection 81 at the end of the winding run to knock the block 76 from the bowl 77, and thereby to render the faller wire 9 inoperative during the outward run of the mule carriage.

Any ordinary means may be employed to elevate the locking lever 75 and thereby to depress the faller rail 9 at the commencement of each winding run of the carriage. For this purpose, I have in Figs. 7 and 8 represented the shaft 60 as provided with a pinion 82 meshing with a gear 83 carried by a suitable bracket 84 and having coaxial therewith a pinion 85 meshing with a rack 86 suitably guided in the bracket 84 and carrying a bowl 87 positioned beneath a shoulder 88 of an arm 89 keyed upon the faller shaft 46, thus rotating said faller shaft and elevating the block 76 of the locking lever 75 to a suitable raising to be received upon the bowl 77. The arm 89 projects downwardly into engagement with a bracket 90 upon the floor to guide the parts during the operation of elevating the locking lever 75 and permitting the block 76 to be moved inwardly upon the bowl 77 at the proper time.

In order to impart the described plurality of to and fro movements to the faller wire 9 during each winding run of the carriage, I provide the upper surface of the coppering rail 65 with a series of swells 91 corresponding in number to the number of to and fro cross winding movements imparted to the cross wind guide 8 during each winding run of the carriage, in this instance four being shown. Each of the said swells is represented as a bracket secured to the coppering rail, though if desired it may be formed integral therewith. Preferably and as indicated the coppering rail is provided with a slight dwell or level part 92 between adjacent swells 91, these dwells permitting the differential movements of the cross wind guide 8 and faller wire 9. It will, however, be understood that the swells 91 may be merged into each other, so that the movement of the faller wire is substantially continuous, and thereby may be wholly synchronous with the movement of the cross wind guide 8.

I provide means to arrest momentarily

the upward movement of the faller wire 9 when it is opposite the apices of the cop noses to take up the yarn at this point as customary. This result I accomplish by 5 providing the inward or right hand end of the coppering rail 65 with a downward incline 93 below the level of the upper edge of said rail and merging into a level portion 94, onto which the bowl 79 rides, therefore 10 by maintaining the faller wire 9 momentarily arrested opposite the apices of the cop noses, as indicated at 9^e in Fig. 10. If desired, the incline 93 may be a continuation 15 of the terminal swell 91. In this manner, I prevent the formation of slack yarns that would otherwise occur at this point, and thus effect in part at least the function heretofore accomplished by driving the spindles at a faster speed during the nosing 20 action.

In spinning mule cops not of the cross wound type, each yarn is wound upon its cop by a succession of close and substantially contacting turns or spirals from base to apex 25 of each conical layer, the yarn being returned from the apex to the base by a series of open turns of much smaller number. For example, in spinning mules not of the cross wound type, there are customarily about 30 twenty turns of yarn in winding from base to apex and six turns from apex to base, the spindles rotating more slowly during the twenty upward turns, although there is a constant acceleration. In the cross wound 35 type of cop formed by the mule herein disclosed there are four upward and four downward movements of the cross wind guide and the faller, and during each up and each of the down movements, the mule 40 as herein organized lays six turns of the yarn upon the cop. It may therefore be desirable to impart a more nearly uniform or even spindle speed during the said four upward winds and the said four downward 45 winds, as said winds are not differentiated from each other as in the former type of cops. This result may be accomplished in any suitable manner, as, for example, by so controlling the quadrant as to impart a minimum 50 oscillation thereto through the usual gear meshing with the rack of the quadrant. I have, however, in Fig. 11 illustrated another form of mechanism similar generally to that heretofore used in twiners and by 55 which the indicated result may be secured. In said figure, I have represented a quadrant motion wherein the winding chain or band 56 passing to the nut 96 of the screw shaft 97 carried by the quadrant 98 is passed 60 about a guide 99 carried by the framing of the head stock, the said winding chain or band passing first about the guide 100 upon the nut, thence about the guide 99, and then again to the nut where the end of it is secured 65 as indicated at 101. In quadrants as

heretofore constructed and adapted to wind cops not of the cross wind type, the quadrant moves in an extended arc and when at the downward limit of its movement extends substantially horizontally, thus compelling greater movement of the winding chain, because the quadrant itself gives off less chain. By the described construction, I am enabled to move the quadrant through a much less arc, approximating substantially 70 one third of that heretofore made necessary and move the nut 96 to a much less extent than heretofore, thereby compelling a more uniform or even spindle speed during the run in of the mule carriage. The winding 75 chain or band 95 has its end opposite that secured upon the nut 96 wound upon a drum 102 which may be and preferably is of substantially uniform diameter throughout the greater portion of its length, but which at 80 one end is provided with a scroll tapering from the diameter indicated to the shaft whereon the drum is mounted. During each winding run of the carriage and at or about the termination of such winding runs the 85 band or chain is received upon such tapering scroll portion of the drum, thereby to speed the spindles up and thus take care of the extra yarn during the nosing action. Such scroll may be used in lieu of the nosing arm 90 of the quadrant commonly employed to bear upon the chain and increase the spindle speed.

From the foregoing description, it will be apparent that by imparting to the faller 100 wire a series of movements during each winding run of the mule corresponding to and either synchronous with or differentiated from the cross wind movements of the guide 8, the tension of the yarns is controlled and the angle of delivery of the yarns past said cross wind guide is controlled at all times, while at the same time by differentiating the movements of the faller and the cross wind guide I secure the effect of the nosing 105 action by imparting increased tension to the yarns as the latter are being wound upon or closely adjacent the apices of the cop noses. By employing a preferably common or conjoint mechanism for imparting the cop 110 building movements to the cross wind wire and to the faller wire and by employing independent means to impart the cross wind movements to the guide 8 and to the faller wire 9, I am enabled absolutely to control 115 the yarns during such cross winding movements and to differentiate the said cross winding movements of the guide 8 and faller wire 9 as may be desired. By employing a coppering rail to impart the cross wind tensioning movements to the faller wire, I greatly simplify the construction of parts.

Having thus described one illustrative embodiment of my invention, I desire it to be understood that although specific terms are 120 125 130

employed, they are used in a generic and descriptive sense and not for purposes of limitation, the scope of the invention being set forth in the following claims.

5. Claims:

1. A spinning mule including in combination spinning spindles, counterfaller means, a cross wind guide distinct from said counterfaller means, means to impart a plurality of to and fro cross wind movements to said guide during a single winding run of the mule, and means independent of said guide to tension the yarns during both directions of cross winding movements imparted thereto by said guide.

10. 2. A spinning mule including in combination driving means, spinning spindles, counterfaller means, a faller, a cross wind guide distinct from said counterfaller means and positioned to engage the yarns between the faller and the spindles, and instrumentalities coöperating with said driving means for imparting to said guide to and fro cross winding movements lengthwise of the spindles, and for imparting cross winding tensioning movements to the faller.

15. 3. A spinning mule including in combination spinning spindles, counterfaller means, a faller, a cross wind guide distinct from said counterfaller means and positioned to engage the yarns between the faller and the spindles, means to impart to said guide to and fro cross winding movements during a single winding run of the mule, and means to impart to the faller cross winding tensioning movements lengthwise of the spindles during such run of the carriage.

20. 4. A spinning mule including in combination driving means, spinning spindles, a faller, a cross wind guide positioned to engage the yarns between the faller and the spindles, and instrumentalities coöperating with said driving means acting during a single winding run of the mule to impart to the said guide and faller cross winding movements, periodically substantially simultaneous but differentiated in extent.

25. 5. A spinning mule including in combination spinning spindles, counterfaller means, a faller, a cross wind guide distinct from said counterfaller means and positioned to engage the yarns between the faller and the spindles, and means to impart vibratory cross winding movements both to the guide and to the faller during a single winding run of the mule.

30. 6. A spinning mule including in combination spinning spindles, counterfaller means, a faller, a cross wind guide distinct from said counterfaller means and positioned to engage the yarns between the faller and the spindles, means to impart cross winding movements to said guide during a single run of the mule, and means to preserve a uni-

35. form winding tension upon the yarn during each cross winding movement of the guide.

7. A spinning mule including in combination spinning spindles, counterfaller means, a faller, a cross wind guide distinct from said counterfaller means and positioned to 70 engage the yarns between the faller and the spindles, means to impart a plurality of advance and return cross winding movements to said guide during a single run of the mule, means to impart an advancing movement to the faller for and during each of said advancing movements of the guide, and means to impart increased tension to the 75 yarn during that part of each advancing movement in which the yarns are laid upon the apices of the cop noses.

8. A spinning mule including in combination spinning spindles, a faller, a cross wind guide positioned to engage the yarns between the faller and the spindles, means to 85 impart a plurality of advance and return cross winding movements to said guide during a single run of the mule, means to impart an advancing movement to the faller for and during each of said advancing movements of the guide, and means to differentiate the said advancing movements of the 90 guide and faller, thereby to impart increased tension to the yarns as they are laid upon the apices of the cop noses.

9. A spinning mule including in combination spinning spindles, counterfaller means, a cross wind guide distinct from said counterfaller means and positioned to engage the 100 yarns adjacent the spindles, means to impart to said guide a plurality of to and fro cross winding movements during a single winding run of the mule, and means coöperating with said guide to prevent the formation of slack yarn during the said cross winding movement of said guide.

10. A spinning mule including in combination spinning spindles, counterfaller means, a cross wind guide distinct from said counterfaller means and positioned to engage the 110 yarns adjacent the spindles, means to impart to said guide a plurality of to and fro cross winding movements during a single winding run of the mule, and means coöperating with said guide whereby the 115 yarns are directed and are equally tensioned at all times during each cross winding movement of the said guide.

11. A spinning mule including in combination spinning spindles, counterfaller means, a faller, a cross wind guide distinct from said counterfaller means and positioned to engage the 120 yarns between the faller and the spindles, mechanism to impart to said guide a plurality of to and fro cross winding movements lengthwise of the 125 spindles during a single winding run of the mule, and coöperating mechanism to im-

part an equal number of to and fro cross winding tensioning movements to the faller during said winding run.

12. A spinning mule including in combination spinning spindles, counterfaller means, a faller, a cross wind guide between the faller and spindles distinct from said counterfaller means, means to impart a plurality of to and fro cross wind movements 5 to said guide during a single winding run of the mule, and a coppering rail coöperating with said faller during the winding runs of the mule, said rail being shaped to impart to the faller during said single winding run 10 a plurality of to and fro cross wind movements.

13. A spinning mule including in combination spinning spindles, counterfaller means, a faller, a cross wind guide between 20 the faller and spindles distinct from said counterfaller means, means to impart a plurality of to and fro cross wind movements to said guide during a single winding run of the mule, and a coppering rail to move said 25 faller during the winding runs.

14. A spinning mule including in combination spinning spindles, counterfaller means, a faller, a cross wind guide between the faller and spindles distinct from said 30 counterfaller means, means to impart a plurality of to and fro cross wind movements to said guide during a single winding run of the mule, and a coppering rail coöperating with said faller during the winding runs of 35 the mule and having faller operating swells equaling in number the to and fro cross wind movements of the guide during a single winding run.

15. A spinning mule including in combination spinning spindles, counterfaller means, a faller, a cross wind guide between the faller and spindles distinct from said counterfaller means, means to impart a plurality of to and fro cross wind movements 40 to said guide during a single winding run of the mule, a coppering rail to move said faller during the winding runs, and means to lower said coppering rail for successive winding runs.

16. A spinning mule including in combination spinning spindles, counterfaller means, a faller, a cross wind guide between the faller and spindles distinct from said counterfaller means, means to impart a plurality of to and fro cross wind movements 45 to said guide during a single winding run of the mule, and a coppering rail coöperating with said faller during the winding runs of the mule and having faller operating swells, 55 said swells having their bases in the same horizontal plane.

17. A spinning mule including in combination spinning spindles, counterfaller means, a faller, a cross wind guide between

the faller and spindles distinct from said 65 counterfaller means, means to impart a plurality of to and fro cross wind movements to said guide during a single winding run of the mule, a coppering rail to move said faller during the winding runs, and means to 70 lower said coppering rail by increments equal at each end of said rail for successive winding runs.

18. A spinning mule including in combination spinning spindles, counterfaller 75 means, yarn tensioning means, a cross wind guide between the tensioning means and the spindles distinct from said counterfaller means, means to impart a plurality of to and fro cross wind movements to said guide 80 during a single winding run of the mule, a coppering rail having a plurality of longitudinally arranged swells, the bases whereof are in substantially the same horizontal plane and connecting means acted upon by 85 the swells of said coppering rail and operatively connected to said tensioning means to impart to the latter a plurality of to and fro tensioning movements during a single winding 90 run of the mule.

19. A spinning mule including in combination spinning spindles, counterfaller means, yarn tensioning means, a cross wind guide between the tensioning means and the spindles distinct from said counterfaller 95 means, means to impart a plurality of to and fro cross wind movements to said guide during a single winding run of the mule, a coppering rail having a plurality of longitudinally arranged swells, the bases whereof are 100 in substantially the same horizontal plane, connecting means acted upon by the swells of said coppering rail and operatively connected to said tensioning means to impart to the latter a plurality of to and fro tensioning movements during a single winding run of the mule, and means for altering the elevation of said rail by increments equal at each end of said rail, for successive winding 105 runs.

20. A spinning mule including in combination spinning spindles, counterfaller means, a cross wind guide distinct from said counterfaller means, means to impart a plurality of to and fro cross wind movements 115 to said guide during a single winding run of the mule, a coppering rail and means governed thereby to tension the yarns during the cross winding movements imparted thereto by said guide.

21. A spinning mule including in combination spinning spindles, counterfaller means, a cross wind guide distinct from said counterfaller means, means to impart a plurality of to and fro cross wind movements 125 to said guide during a single winding run of the mule and means having a to and fro movement during a single winding run of

the mule and coöperating with said guide, whereby the latter controls the angle of delivery of the yarns past the guide to the spindles during said cross wind movements.

- 5 22. A spinning mule including in combination spinning spindles, counterfaller means, a cross wind guide distinct from said counterfaller means and engaging one side of the yarns, means to impart a plurality of to and fro cross wind movements to said guide during a single winding run of the mule, a device engaging the opposite side of said yarns, and means to impart tensioning movements thereto during a single cross winding movement of the guide, whereby said guide controls the angle of delivery of the yarns past the same to the spindles during said cross winding movements.

- 10 23. A spinning mule including in combination spinning spindles, a faller, a cross wind guide positioned to engage the yarns between the faller and the spindles, means to impart to said guide a plurality of forward and return cross winding movements during a single winding run of the mule, and means to impart to said faller an equal number of forward and return movements during said winding run and to terminate each forward movement of the faller prior 15 to the termination of the corresponding movement of the guide.

- 20 24. A spinning mule including in combination spinning spindles, a faller, a cross wind guide positioned to engage the yarns between the faller and the spindles, means to impart to said guide a plurality of to and fro cross winding movements during a single winding run of the mule, and means to impart a plurality of tensioning movements 25 to the faller during said winding run, said tensioning movements being variable with respect to said cross winding movements.

- 25 25. A spinning mule including in combination driving means, spinning spindles, counterfaller means, a faller, a cross wind guide distinct from said counterfaller means and coöperating with the faller, instrumentalities coöperating with the driving means to impart to the faller and to the guide a single, synchronous cop building movement for each of a plurality of winding runs of the mule, and means to impart to said guide and to said faller a plurality of cross winding movements for a single winding 30 run of the mule.

- 35 26. A spinning mule including in combination driving means, spinning spindles, a faller, a cross wind guide coöperating with the faller, instrumentalities coöperating with the driving means to impart to the faller and to the guide a single, synchronous cop building movement for each of a plurality of winding runs of the mule, means to impart to said guide a plurality of cross winding movements for a single winding 40 run of the mule.

run of the mule and independent means to impart a plurality of variable, tensioning movements to the faller during said single winding run.

- 5 27. A spinning mule including in combination spinning spindles, a cross wind guide adjacent thereto, a longitudinally movable shaft operatively connected to said guide to reciprocate the same and carrying two cams of different pitch, two movable members each having a projection to engage one of said cams, a support for said members, means gradually to elevate said support during the building of the cops, a member carried by the frame and provided with a cam way and a movable connection between said cam way and said members to control the engagement of their projections with said cams.

- 10 28. A spinning mule including in combination spinning spindles, a cross wind guide adjacent thereto, a longitudinally movable shaft operatively connected to said guide to reciprocate the same and carrying two cams of different pitch, two movable members each having a projection to engage one of said cams, a support for said members, means gradually to elevate said support during the building of the cops, a guide, and means moved thereby during the elevation 15 of said support to control the engagement of said projections with said cams.

- 20 29. A spinning mule including in combination spinning spindles, a cross wind guide adjacent thereto, a longitudinally movable shaft operatively connected to said guide to reciprocate the same and carrying two cams of different pitch, two movable members each having a projection to engage one of said cams, a support for said members, means gradually to elevate said support during the building of the cops, a guiding cam carried by the framing, a lever movable with said support, and adapted to be shifted by said guiding cam, and connections between 105 said lever and said movable members to control the engagement of their projections with said shaft cams.

- 25 30. A spinning mule including in combination spinning spindles, a cross wind guide, means to impart a plurality of to and fro cross wind movements to said guide during a single winding run of the mule, and means independent of said guide to tension the yarns during both the to and the fro cross 110 winding movements imparted thereto by the guide.

- 30 31. A spinning mule including in combination spinning spindles, counterfaller means, a cross wind guide distinct from said counterfaller means, means to impart a plurality of up and down cross winding movements to said guide during a single winding run of the mule, and means distinct 115 from said guide to tension the yarns during 120

the downward cross winding movements of the guide.

32. A spinning mule including in combination spinning spindles, counterfaller 5 means, a cross wind guide distinct from said counterfaller means, means to impart a plurality of to and fro cross winding movements to said guide during a single winding run of the mule, and tensioning 10 means having a plurality of to and fro yarn tensioning movements during a such single winding run.

33. A spinning mule including in combination spinning spindles, counterfaller 15 means, a faller, a cross wind guide distinct from said counterfaller means positioned to engage the yarns between the faller and the spindles, means to impart to said guide to and fro cross winding movements length- 20 wise of the spindles, and means independent of said guide operating means to impart cross winding tensioning movements to the faller.

34. A spinning mule comprising in combination spinning spindles, a movable cross-winding guide, and means independent thereof to tension the yarn throughout the entire movement of the yarn across said guide and irrespective of the direction of movement of said guide. 25 30

35. A spinning mule including in combination spinning spindles, a cross-winding guide, means to move the guide up and down the spindles, and yarn-tensioning means independent of said guide and constructed and operated to impart equal tension to the yarn at all times, whether the cross-winding guide be moving up or be moving down the spindles. 35

In testimony whereof, I have signed my 40 name to this specification, in the presence of two subscribing witnesses.

JOHN LOWE.
